FIGURE TOY

Filed June 16, 1927

FIG. 1.

FIG. 3.

FIG. 2.

Inventor:

Jacob H. Kutz
Norman B. Miller

By

Attorney.

UNITED STATES PATENT OFFICE.

JACOB H. KUTZ, OF BETHLEHEM, PENNSYLVANIA.

FIGURE TOY.

Application filed June 16, 1927. Serial No. 199,350.

The present invention relates to **toys**, and aims to provide a novel and improved wheel-mounted figure toy which will be amusing and entertaining for children.

5 Another object of the invention is the provision of such a toy having a figure representing a horse or other animal and novel means for mounting and operating the body and legs thereof so that the figure has a 10 realistic running motion when the toy is moved over the floor.

With the foregoing and other objects in view, which will be apparent as the description proceeds, the invention resides in the 15 construction and arrangement of parts, as hereinafter described and claimed, it being understood that changes can be made within the scope of what is claimed, without departing from the spirit of the invention.

20 The invention is illustrated in the accompanying drawing, wherein—

Figure 1 is a section on the line 1—1 of Fig. 3, showing the figure in elevation.

Figs. 2 and 3 are sections on the respective lines 2—2 and 3—3 of Fig. 1.

A small truck is provided to roll on the floor, and comprises a plate or deck 7, which may be of wood, mounted on the axles 8 of wheels 9, and a string 10 or other suitable element is connected to the forward end of the plate 7 for pulling the toy about on the floor.

The figure, which may represent a horse or other animal, comprises a body 11 mounted for rocking or oscillatory motion between its ends on a wire standard 12 secured to and rising from the plate 7, and the legs 13 of the figure are pivoted to the opposite sides of the body 11 by means of screws 14, so that the body 11 may oscillate about a transverse axis and the legs 13 may also oscillate relatively to the body about the transverse axes of the screws 14.

In order to oscillate the body 11 when the toy is moved on the floor, a link 15 is pivotally connected, as at 16, to the rear end of the body 11, and the lower end of the link is connected to a crank 17 with which the rear axle 8 is provided, so that the rotation of said axle will rock the body 11 on its fulcrum.

The legs 13 of each pair are oscillated for-

wardly and rearwardly in opposite directions, by means of wire links 18 having their upper terminals located between the body 11 and legs and provided with outturned pivot portions 19 engaging in the legs 13 of the corresponding pair in front and in rear of the pivot axis of said pair of legs. The lower ends of the links 18 of each pair are pivotally connected with the truck. As shown, the lower ends of the links 18 of each pair are connected by a yoke 20 which pivotally engages through a reduced terminal 21 of a piece 22 cemented or otherwise secured within a slot 23 in the plate or board 7 so that the pieces 22 are flush with the plate or board 7. The wire is resilient in order that the links 18 of each pair may swing slightly relatively to one another, and when the body 11 is oscillated, the upward and downward movement of the pivots 14 will result in the legs 13 being swung forwardly and rearwardly, thereby giving the figure a realistic running motion.

The rear slot 23 is extended in order to accommodate the link 15 and crank 17.

The plate 7, wheels 9, body 11 and legs 13 may be made of wood, while the links 15 and 18 and axles 8 may be made of wire, so that the toy may be inexpensively manufactured.

Having thus described the invention, what is claimed as new is:—

1. A toy comprising a truck, an animal figure having a body mounted for oscillation on the truck and having legs pivoted to the body, means for oscillating the body, and links pivotally connected with said legs in front and rear of the pivot axes of the legs and pivotally connected with the truck to swing the legs forwardly and rearwardly in opposite directions when the body is oscillated.

2. A toy comprising a truck, an animal figure having a body mounted for oscillation on the truck and having legs at opposite sides of and pivoted to the body, means for oscillating the body, and links pivotally connected at their lower ends with the truck and having their upper terminals extending between the body and legs and pivotally connected with said legs in front and in rear of the pivot axes of the legs to swing the

legs forwardly and rearwardly in opposite directions when the body is oscillated.

3. A toy comprising a truck including a plate having slots, an animal figure having a body mounted for oscillation on the truck and having legs pivoted to the body, means for oscillating said body, links connected to

said legs, and pieces to which the links are connected and secured within said slots flush with the plate.

In testimony whereof I hereunto affix my signature.

JACOB H. KUTZ.
